UNITED STATES PATENT OFFICE

ALEXANDER A. SKVORTZOFF, OF SHARON, PENNSYLVANIA, ASSIGNOR TO WESTINGHOUSE ELECTRIC & MANUFACTURING COMPANY, A CORPORATION OF PENNSYLVANIA

CONDUCTOR FOR TRANSFORMERS

Application filed September 2, 1926, Serial No. 133,101. Renewed January 18, 1929.

My invention relates to oil insulated apparatus and particularly to means for preventing the creepage of oil from such apparatus along the conductors passing through 5 the walls thereof.

One object of my invention is to provide an internal conductor for oil-immersed electrical apparatus that shall prevent the creepage of oil along the insulating material surrounding 10 the conductor.

Another object of my invention is to provide a conductor for oil-immersed electrical apparatus, that shall have the continuity of the insulating material interrupted for the 15 purpose of preventing the creepage of oil along the conductor by a siphonic and capillary action.

In electrical oil insulated apparatus in which the electrical conductors are passed directly through a bushing, trouble is frequently experienced by reason of the creepage of the oil outwardly of the apparatus along the insulating material surrounding the conductors. 20

I propose to eliminate the foregoing difficulty by interrupting the continuity of the insulating material surrounding the conductors at the level of the insulating liquid by interposing a body of non-porous material around the metallic part of the conductor. 25

In the accompanying drawings,

Fig. 1 is a view, partially in elevation and partially in section, of an electrical transformer embodying my invention; 30

Fig. 2 is a sectional view of one form of my invention; and

Fig. 3 is a sectional view of a modified form of my invention.

My invention comprises, in general, a casing 1 in which is mounted an electrical device 2, such as a transformer, that is surrounded by a body of insulating oil 3 and which is connected externally of the casing 1 by conductors 4 that pass through suitable bushings 5. 40

The conductors 4 are provided with sections 6 of non-porous material secured directly to the metal of the conductor from 45 which the porous insulating material has

been removed, for preventing the creepage of the oil 3 along the porous insulating material 7 surrounding the portions of conductors 4 extending through the bushings 5.

Referring to Fig. 2, the section 6 is preferably made of micarta, or any other non-porous insulating material mounted on the metallic portion of the conductor 4, and is placed at the normal level of the insulating oil 3. Since the section 6 is of non-porous material, the creepage or flow of the insulating oil 3 upwardly along the conductor 4 and insulating material 7 is prevented. 55

Referring to Fig. 3 I have shown a modified form of my invention in which the non-porous section is formed by a plurality of layers of micarta paper 8 rolled upon the conductor 4. The operation of this form of my invention is substantially the same as that shown in Fig. 2. 60

Accordingly, I have provided a means for preventing the creepage or flow of insulating oil from electrical apparatus which provides for interrupting the continuity of the porous insulating material normally surrounding such conductors and replacing it with a non-porous section of insulating material that is disposed at the normal level of the insulating fluid. 75

While I have described and illustrated but two embodiments of my invention, it will be obvious to those skilled in the art that various changes, modifications, substitutions, additions and omissions may be made in the apparatus illustrated without departing from the spirit and scope of the invention, as set forth in the appended claims. 80

I claim as my invention:

1. In combination, a casing, a liquid therein, and a wire having a coating of porous material extending through the casing and into the liquid, of a section of non-porous material inserted into the coating at approximately the level of the liquid to prevent siphoning and capillary actions in the coating. 90

2. In combination, a casing for an electrical device, a liquid therein, and a conductor having a coating of porous insulating material extending through the casing and into the liquid, of a section of non-porous mate- 100

rial inserted into the coating and a portion only of which is disposed above the level of the liquid to prevent siphoning and capillary actions in the coating.

3. In combination, a casing for an electrical device, a liquid therein, and a conductor having a coating of porous insulating material extending through the casing and into the liquid, of a section of non-porous material interrupting the continuity of the insulating material at the level of the liquid for preventing creepage of the liquid along the insulating material.
4. In combination, an electrical conductor, insulating material surrounding a portion of said conductor, and means for preventing the creepage of liquid along the insulating material surrounding the conductor, comprising a body of non-porous material around the conductor.
5. In combination, an electrical conductor, insulating material surrounding a portion of said conductor, and a body of non-porous material around a section of the conductor to prevent the creepage of liquid along the conductor.

In testimony whereof, I have hereunto subscribed my name this 13th day of August, 1926.

30 ALEXANDER A. SKVORTZOFF.
